UNITED STATES PATENT OFFICE.

HENRY M. KINPORTS, OF BOSTON, MASSACHUSETTS.

DESIGN FOR A RATAN OR WICKER CHAIR.

SPECIFICATION forming part of Design No. 29,995, dated January 10, 1899.

Application filed November 19, 1898. Serial No. 696,940. Term of patent 3½ years.

To all whom it may concern:

Be it known that I, HENRY M. KINPORTS, of Boston, in the county of Suffolk and State of Massachusetts, have invented a certain new and original Design for a Ratan or Wicker Chair, of which the following is a sufficiently full, clear, and exact specification.

Reference is to be had to the accompanying drawing, forming a part of this specification, which drawing is a perspective view of a ratan or wicker chair, showing my new design.

As represented in the drawing, the leading features of my design consist of the inward and downward curve of the upper ends of the side rolls $a a'$. From their upper curved ends the side rolls are extended downward to the arms d in an inwardly-inclined direction, though parallel with the standards $b b'$, which intersect the aforesaid extreme inward and

downward curved ends of the side rolls. The 20 head-rest e and back-rest f are curved downward from their ends in the space c between the standards $b b'$.

g designates the seat, and h the base, of the chair. 25

Having described my invention, I declare that what I claim as new is—

The design for a ratan or wicker chair as herein shown and described.

In testimony whereof I have signed my 30 name to this specification, in the presence of two subscribing witnesses, this 16th day of November, A. D. 1897.

HENRY M. KINPORTS.
